POWER LAWN MOWER

Acial Cataline, Holt, and Granville R. Conrad,
Lansing, Mich., assignors to Reo Motors, Inc.,
Lansing, Mich., a corporation of Michigan

Application November 8, 1952, Serial No. 22,207

Term of patent 14 years

(Cl. D40--1)

To all whom it may concern:

Be it known that we, Acial Cataline and Granville R. Conrad, citizens of the United States of America, residing in the city of Holt and city of Lansing, respectively, county of Ingham, State of Michigan, have invented a new, original, and ornamental Design for a Power Lawn Mower, of which the following is a specification, reference being had to the accompanying drawing, forming a part thereof, wherein:

Figure 1 is a perspective view of a power lawn mower, showing our new design.

Figure 2 is a perspective view thereof showing the opposite side and rear end. The dominant

features of the design reside in the portions shown in full lines.

We claim:

The ornamental design for a power lawn mower, substantially as shown and described.
